PAUL H. CARPENTER, OF KENT, OHIO

METHOD OF MAKING NURSING NIPPLES

Application filed March 20, 1929. Serial No. 348,527.

This invention relates to an improvement in rubber nipples for nursing bottles, and one of the principal objects thereof is to provide a nipple in which the discharge aperture is so formed that the cross sectional area thereof when the nipple is collapsed while in use, is not decreased, with the result that the flow of food is not impeded or stopped, by reason of the aperture partially or wholly closing when the nipple is collapsed.

I attain this object by forming the nipple with a funnel-shaped aperture which tapers from the inner surface to near the outer surface of the nipple, the cross sectional area of the aperture being greatest at the inner end thereof.

A further object of the invention is to provide a method of perforating the nipples such as will render the walls defining the perforations perfectly smooth and free of interstices, and such as will insure the perforations being properly shaped.

The foregoing object is accomplished by perforating the rubber forming the end of the nipple, with a die and punch, while the rubber is under tension. The hole is made of such dimension as, in ordinary use when the nipple is collapsed, to leave a free open passageway for the food and at the same time to avoid an excessive flow thereof.

It is well known to physicians and professional nurses, that rubber nursing nipples as now commercially manufactured ordinarily have many defects. Among these may be mentioned that the perforations are oft times not extended clear through the walls of the nipple, or are of irregular cross section, or are too small, or are bounded by walls which are rough or unsmooth. Another objection is that the perforations ordinarily are of the same, or approximately the same cross section throughout their length.

These imperfections attending the ordinary commercial nipple, are indeed, so well recognized that many hospitals order unperforated nipples for their use, and have perforations made by hand at the hospital. The method ordinarily used to form the per-

forations by hand at is to heat the end of a cambric needle to red heat and burn the desired number of perforations in the nipple. Not only do many of the hospitals and professional nurses thus resort to burning the perforations in the nipple by hand, but also in the home, it is quite common to see a mother burning a perforation in a nipple with a hot needle.

The nipple openings thus formed, however, are still objectionable for the reason that it is extremely hard to control the burning operation to obtain openings of just the desired size, and further, the openings obtained are ordinarily of the same diameter throughout and the walls are ordinarily not smooth, but like the commercial nipple, are subject to the accumulation of particles of food.

Further, the openings being of substantially constant diameter, the crowding of the walls upon collapse of the nipple in the child's mouth, causes the opening to oft times entirely close, particularly at the inner end thereof, and thus retard or stop the passage of food. It is a matter of common experience that many nipples, both those commercially finished, and those perforated by hand often collapse to such an extent that the sides of the walls of the nipple adhere together and the nipple has to be taken from the child's mouth and the walls either forced apart or the nipple lifted slightly from the mouth of the bottle in order to admit air sufficient to break the seal.

In carrying out my invention, two essentials which eliminate much of the objections to the commercial nipple, are borne in mind. These are, that the walls of the opening are made smooth, and, more important, that the opening is so formed as not to close upon collapse of the nipple, thereby allowing for a continuity in the flow of food, and the prevention of the formation of a seal such as would cause the nipple walls to adhere together.

In the accompanying drawings which illustrate an embodiment of the invention, Figure 1 is a view in elevation, partly

broken away, illustrating on a large scale, a nipple constructed according to my invention.

Fig. 2 is a fragmentary enlarged sectional view of the tip of a nipple constructed according to my invention, showing the shape of the opening therein, and showing the plug of rubber which is cut from the nipple to form the opening.

Fig. 3 is an elevational view, partially in section, of a device which may be utilized in manufacturing nipples according to my invention, and

Fig. 4 is an enlarged detail sectional view of the nipple holder and guide and associated parts of the punching device illustrated in Fig. 3.

Referring more particularly to the drawings, a nipple 5, constructed according to my invention, may be shaped as usual, and may have walls 6 formed of the usual thickness and of the usual grade or grades of rubber. The perforation in the end 7 of the nipple, however, departs from the former practice, in that the perforation is funnel-shaped at its inner portion, as at 8, and tapers to a short substantially cylindrical outer portion 9, which leads to the outer surface of the nipple. The diameter of the inner end of the perforation is many times that of the outer end, and the perforation is so cut that the walls thereof are smooth and free from small irregularities or interstices which might accumulate food particles.

While I have illustrated the perforation as having a funnel-shaped inner portion, merging with a substantially cylindrical outer portion, it will be understood that a nipple having a perforation of continuous funnel shape with the funnel tapering from the inner to the outer surface of the nipple, is as readily made in following the method comprising my invention.

One of the main advantages obtained by my invention, resides in the fact that when the nipple is collapsed or partially collapsed, the continuity of the perforation will be maintained, despite the fact that the pressure upon the rubber around the perforation tends to close the opening. It has been found that the crowding of the rubber around the perforation of a nipple in use, has a marked tendency to bring the walls of the perforation together, particularly at the inner end of the opening, and thus by widening the opening at the inner end, this tendency is compensated for. For instance, the nipple when collapsed or partially collapsed in use, may distort the shape of the opening from a substantially conical one, to a substantially cylindrical one, but the continuity of the opening comprising the portions 8 and 9, will be maintained. The aperture at the apex of the cone in a nipple constructed in accordance with my invention

determines the rate of flow of the food. This aperture should be of such size as to provide a free flowing nipple, i. e., one through which the child may draw the food without excessive effort. At the same time this aperture should be sufficiently small as to prevent "flooding."

On the other hand, in the usual commercial nipple, made originally with a substantially cylindrical opening, the crowded condition of the rubber when the nipple is collapsed or partially collapsed in use oftentimes effects a closing of the perforation, particularly toward the inner end thereof, and thus effectually retards or stops the flow of food. Further the walls of the perforations in the commercial nipple are commonly irregular or rough, with the result that food particles gather therein which are extremely difficult of removal.

The method which I employ for perforating nipples is illustrated in Figs. 3 and 4 of the drawings.

A simple mechanism which may be used, includes a base 15 on which a die 16 is mounted. The die opening 17 alines with a larger opening 18 in the base, through which the plugs of rubber 19 (see Fig 2) cut from the nipple in forming the perforations, may drop. A punch 20 having a conical lower end 21 is alined with the die, by means of a braced guide 22 through which the punch may reciprocate. A nipple holder and guide 23 is mounted on the base above the die, and includes a funnel-shaped body portion 24 which receives the nipple to be perforated, and supports it, as indicated in the drawings. The nipple holder 24 may be so proportioned that the bulged portion 25 of the body of the nipple, and the bulged portion 26 at the end of the nipple may snugly fit within the body when the nipple is dropped therein. The lower portion of the nipple holder 24 is provided with an opening 27. This opening is of such diameter that when the punch is lowered, after the nipple has been placed in the holder, the end of the punch will draw the tip of the nipple out through the opening 27 to the desired tension, and the distance of the lower end of the nipple holder above the die 16 is likewise so proportioned that the proper and desired tension upon the rubber at the tip of the nipple will have been obtained when the punching operation begins.

The method of operating the device is as follows:

An unperforated nipple is dropped into the holder 24, while the punch is elevated. The punch is then brought down, the conical end thereof engaging the tip of the nipple and stretching the rubber over the punch, and as the latter passes through the opening 27, draws the rubber under tension through such opening. When the die 16 is

engaged, and the initial cut made on the outer surface of the rubber, the rubber will be in a distorted and stretched condition, and as the punch is further lowered, it is 5 preferably rotated as the cut is continued, although the rotation of the punch is not essential.

As soon as the initial cut at the outer skin of the rubber is made, the rubber in 10 tending to assume its shape, draws back, and this withdrawal of the outer skin of the rubber, together with the continuing descent of the plunger and consequent continuous pressure on the inner side of the 15 rubber, causes the cut to depart from its initial direction with respect to the surface of the nipple, and taper toward the punch, with the result that when the punch is withdrawn and the nipple assumes its shape, the 20 perforation is found to be as described. The explanation of why the funnel-shape is imparted to the cut, which I have just given, is, I believe, the correct one, but whether it is in all details correct or not, it remains 25 a fact that a conical perforation is formed in the nipple when it is stretched over the punch and brought into cutting contact with the die.

The plug 19 cut from the nipple, is 30 pressed through the die opening and drops through the opening 18 in the base 15.

I have found by actual experience, that the perforation thus formed in a nipple, is 35 smooth and regular, and free from the objections to the ordinary perforations as set out above, and that the nipples in use are particularly advantageous in eliminating many of the objections to the ordinary perforated nipples.

40 The size of the openings formed by my method of perforation can be determined by selecting a punch and die of the desired dimensions.

The foregoing description has been given 45 for clearness of understanding, and no undue limitations should be deduced therefrom, but the appended claim should be construed as broadly as permissible, in view of the prior art.

60 Having thus described my invention what I claim as new, and desire to secure by Letters Patent is:—

The method of forming an opening in a 55 nipple, which consists in stretching a zone of the nipple over a tapered form and severing the stretched and tapered portion around a circumference thereof by a single cut.

65 In testimony whereof, I hereunto affix my signature.

PAUL H. CARPENTER.
